UNITED STATES PATENT OFFICE.

ALICE O. McCORD, OF COLFAX, WASHINGTON TERRITORY.

AUTOMATIC STEM-PESSARY.

SPECIFICATION forming part of Letters Patent No. 372,922, dated November 8, 1887.

Application filed December 31, 1886. Serial No. 223,126. (Model.)

To all whom it may concern:

Be it known that I, ALICE O. McCORD, a citizen of the United States, residing at Colfax, in the county of Whitman and Territory 5 of Washington, have invented a new and useful Automatic Stem-Pessary for Use in the Treatment of Diseases of the Womb, of which the following is a specification.

My invention is a cervical cup and intra-uterine stem attached for the purpose of applying medicine to the cervix uteri and holding it in place during treatment of diseased condition of the womb.

Figure 1 is a side view of the stem of the 15 pessary. Fig. 2 is a sectional view showing the practical application of the pessary. Fig. 3 is a perspective view of the pessary.

The instrument consists of a conical cup (see Fig. 3) of hard or soft rubber or any other 20 material suitable, with a central stem on the concave surface, which stem may equal or exceed the height of the cup, as occasion requires, in treating different diseases of the cervix, said stem to be cylindrical in form, but swelled 25 at each extremity and perforated with a central cavity from the face extremity to within one-fourth of an inch of its base, where it terminates in a cross-slot, (see Fig. 2,) the perforated stem answering the double purpose of 30 keeping the instrument in place and also for

applying and equally distributing medicine to the endometrium of the cervix.

The advantages of the instrument are that any medicine may be applied to the neck of the womb and the cervical endometrium at 35 the same time, and the medicine held in place during the entire day or night without inconvenience to the patient, the action of the vaginal wall upon the yielding surface of the cup constantly irrigating the inner surface of the 40 neck of the womb through the vertical and transverse cavities of the central stem, (see Fig. 2,) and the same returning between the stem and cervical wall.

I am aware that patents have been granted 45 for rubber pessaries having a stem provided with perforations to allow the secretions of the uterus to escape. This I disclaim.

What I do claim is—

As a new article of manufacture, the soft- 50 rubber pessary hereinbefore described, the same consisting of the concavo-convex part and the stem having longitudinal and cross-slots in its upper portion and projecting from the concave side of the other part, with which 55 it is molded integrally, as described.

ALICE O. McCORD.
